UNITED STATES PATENT OFFICE.

WILLIAM C. FISHER, OF MIDDLETON, CONNECTICUT.

CARTRIDGE-POCKET.

No. 918,837.

Specification of Letters Patent.

Patented April 20, 1909.

Application filed July 14, 1908. Serial No. 443,460.

To all whom it may concern:

Be it known that I, WILLIAM C. FISHER, of Middletown, in the county of Middlesex and State of Connecticut, have invented certain new and useful Improvements in Cartridge-Pockets; and I do hereby declare the following to be a full, clear, and exact description of the invention, such as will enable others skilled in the art to which it appertains to make and use the same.

This invention relates to improvements in cartridge pockets such as are employed on woven-fabric cartridge belts,—the object of the present invention being to provide a cartridge pocket having a partition to adapt the pocket for the reception of two clips of cartridges, and to effectually reinforce the bottoms of both of the compartments thus formed.

20 A further object is to provide a divided cartridge pocket having its bottom portion reinforced to prevent the penetration of pointed projectiles, and to utilize the fabric partition to form a cover for one of the compartments of the pocket.

25 With these objects in view the invention consists in certain novel features of construction and combinations of parts as hereinafter set forth and pointed out in the claims.

30 In the accompanying drawings, Figure 1 is a perspective view, partly in section, of a portion of a cartridge belt embodying my improvements. Fig. 1^a is an enlarged sectional view showing the bottom portion of a pocket. Fig. 2 is a separate view of the portions which form the partition, the covers for the compartments of the pocket, and the reinforcement for the bottom portion of the pocket. Fig. 3 is a sectional view of a cartridge pocket showing an embodiment of a modified form of my invention, and Fig. 4 is a separate view of the modification shown in Fig. 3.

35 1 represents a portion of a woven-fabric cartridge belt and 2 a woven-fabric cartridge pocket thereon.

40 A fabric strip 3 is located within the pocket 2 against the rear wall thereof and is secured to the said rear wall near the upper edge thereof by means of eyelets 4 or in any other suitable manner. The upper portion 5 of the strip 3 which extends above the pocket is made somewhat wider than the portion within the pocket and constitutes a flap or 45 cover for the latter. This flap or cover 5 is provided with one member 6 of a fastening

device, the other member 7 of the latter being located on the outside of the pocket. The lower end of the strip 3 extends over the bottom of the pocket and its free edge is secured to the front wall of the latter. Before the strip 3 is placed in the pocket, a reinforce 60 8 of wire cloth, leather or other material capable of resisting the penetration of pointed projectiles, is secured to the rear face of said strip 3 in proximity to the end thereof within the pocket, so that when the strip is secured in position, as above explained, the reinforce 8 will become disposed over the bottom of the pocket and under that 65 portion of the strip 3 which extends over the bottom of the pocket. The reinforce thus located will prevent the penetration of pointed projectiles through the bottom of the pocket and that portion of the strip 3 over 70 the reinforce will serve as a cushion to prevent the rattling of the projectiles against the reinforce when the latter is made of metal.

75 A fabric partition 9 for the pocket extends upwardly from the lower portion of the strip 3 a short distance from the extremity of said strip and projects beyond the top of the pocket,—the portion 10 which projects beyond the top of the pocket, constituting a flap or cover for one of the compartments formed 80 by the partition and this flap or cover is provided with one member 11 of a fastening device, the other member 12 of which is secured to the cartridge pocket. The partition 9 and cover 10 thus formed serve to confine a clip 85 of cartridges closely within one compartment of the pocket, while the cover 5 will close the other compartment and also confine the cover 10. As the cover 10 is held in place by the cover 5 the fastening devices 11—12 for 90 the cover 10 may be omitted.

95 In the form of the invention shown in Figs. 3 and 4, a fabric tube 13 closed at its lower end, projects upwardly from the lower end of the strip 3. One wall of the tube 13 100 projects above the cartridge pocket and forms a cover 14 for the compartment of the pocket which is affected by said tube. The other wall of the tube terminates a short distance below the upper edge of the front wall 105 of the pocket and is secured thereto. A reinforce 15 is located under the lower end of the tube and the lower portion of the strip 3 so as to be disposed over the bottom of the pocket and serves to prevent the penetration 110 of projectiles through the bottoms of both compartments of the pocket.

Having fully described my invention what I claim as new and desire to secure by Letters-Patent, is,—

1. The combination with a cartridge pocket, of a member secured therein, said member having a part extending over the bottom of the pocket and also having a part projecting above the pocket to form a cover, and a second member projecting upwardly from the lower portion of the first mentioned member and forming a partition in the pocket, said second member projecting above the pocket and constituting a cover for one of the compartments of the pocket.
2. The combination with a woven fabric cartridge pocket, of a woven strip secured to the rear wall of the pocket and extending above the latter to form a cover for the pocket, a reinforce secured to the lower portion of the strip, said lower reinforced portion of the strip extending over the bottom portion of the pocket and secured at its end to the front wall of the latter, and a partition in the pocket extending from the reinforced portion of the strip and projecting beyond the top of the pocket.
3. The combination with a cartridge pocket, of a strip secured therein and having a portion disposed over the bottom of the pocket, a reinforce secured to said strip and disposed between the same and the bottom of the pocket, said strip having an extension forming a cover for the pocket, a partition for the pocket projecting upwardly from the lower portion of said strip, and a cover for one of the compartments formed by said partition, said cover constituting an extension of said partition.

4. The combination with a cartridge pocket, of a strip secured therein and having a portion extending over the bottom of the pocket and a portion projecting above the pocket and constituting a cover for the latter, and a partition secured to the lower portion of the strip and dividing the pocket into two compartments, the upper portion of said partition extending above the top of the pocket and constituting a cover for one of said compartments, and fastening devices for said covers.

5. The combination with a cartridge pocket, of a strip secured therein, a reinforce disposed over the bottom portion of the pocket and secured to said strip and means projecting upwardly from the lower portion of the strip and dividing the pockets into two compartments, said dividing means and the strip projecting above the pocket and constituting covers for the compartments thereof.

6. The combination with a cartridge pocket, of a strip secured therein and having a portion disposed over the bottom of the pocket, and a partition for the pocket projecting upwardly from the lower portion of said strip, said partition projecting above the top of the pockets and constituting a cover for one of the compartments thereof.

In testimony whereof, I have signed this specification in the presence of two subscribing witnesses.

WILLIAM C. FISHER.
